UNITED STATES PATENT OFFICE.

DAVID GROVE, OF BERLIN, GERMANY.

DRIER.

SPECIFICATION forming part of Letters Patent No. 313,416, dated March 3, 1885.

Application filed February 28, 1883. (No model.) Patented in Germany January 29, 1883, No. 23,722; in England January 29, 1883, No. 469; in Belgium February 7, 1883, No. 60,375, and in France February 15, 1883, No. 153,731.

To all whom it may concern:

Be it known that I, DAVID GROVE, of the city of Berlin, and German Empire, have invented certain new and useful Improvements 5 in Drying or Arefying Apparatus for Meat and other Materials, of which the following is a specification.

The object of this said invention is to dry or arefy meat and other substances in a rapid 10 rational manner by employing heated air. The meat or other material to be dried is turned or shifted in such manner that a thoroughly equable drying or arefaction is attained and all adhesion to the shelves or sieves 15 prevented.

The accompanying drawings show an apparatus for drying or arefying meat, consisting of an air-heating arrangement, the drying or arefying chambers placed or fixed immediately 20 above the said air-heating arrangement, and the mechanical devices for operating the said apparatus.

Figure 1 is a section of the apparatus on the line C D in Fig. 2. Fig. 2 is a vertical longitudinal section on the line A B in Fig. 4. Fig. 3 is a cross-section on the line G H in Fig. 4. Fig. 4 is a horizontal longitudinal section of the apparatus just beneath the roof of the furnace. Fig. 5 is a front elevation showing 30 the mechanical arrangement for moving the shelves or sieves in the arefying or drying apparatus. Fig. 6 is a cross-section of Fig. 4 on the line E F. Fig. 7 is a section of the sieves, and Fig. 8 is a perspective view with 35 some parts broken away to show others of the drying-chambers and their immediate appurtenances.

The furnace or air - heating apparatus Z is located so low beneath the ground or flooring 40 that the drying or arefying chambers M can be served with facility. The combustion-chamber 5, above the fire-bars 6, is surrounded by walls 7, of fire-proof clay or other suitable refractory material, which said walls are held 45 by suitable cast-iron plates, 8. These said walls of refractory material are provided with four canals or flues, 1 2 3 4, for introducing air into the combustion-chamber. This said air passes through the canals or flues in the 50 direction given by the arrows, becomes heated through contact with the hot walls of the said

canals or flues, and passes through suitable openings, 9, in the upper canal or flue, 4, into the combustion-chamber, and thus serves to so promote the combustion of the inflammable 55 gases present in this said chamber that perfect combustion ensues and all smoke is prevented.

The sliding doors 10 11 to the furnace and ash-pit, respectively, are arranged to shut air-tight, and are further so arranged that they can be readily slid in each direction, in order to be able to regulate the amount of air introduced into the furnace in any ordinary manner. The products of combustion stream 65 through cast-iron pipes or tubes a a' b b' c c', in the direction given by the arrows, into the flue 13, and so to the chimney. These pipes a a' b b' c c' are provided with suitable ribs or projections, 14, to increase their heating-surface. The end flanges of the aforesaid ribbed pipes or tubes a a' b b' c c' are so supported in suitable bearings, h, filled with fine sand, that the said tubes or pipes can readily expand and still preserve a smoke-tight joint. The 70 junction of the pipes or tubes in the heating-compartment is made by carefully planing the flanges and screwing them up tight against asbestos or other suitable packing. Suitable cleaning doors or openings, 15 16, are arranged 75 in the flue, and also at the ends of the aforesaid pipes or tubes, respectively. The drying or arefying chambers M are situate above the heating-chamber. Cast-iron supports G are connected to the upper cast-iron frame, 80 H, and form in connection therewith the framework in which the surrounding sheet-metal walls K N and the separate arefying or drying chambers M are attached. The outer walls or casing, K, are provided with a suitable 85 covering of non-conducting material in order to prevent radiation. The floors or bottoms L of the drying or arefying chambers M are composed of zinc, galvanized corrugated sheet-iron, sheet-zinc, or other suitable material. 90 The longitudinal walls N are made of perforated sheet metal, in order to permit the heated air to enter and also to leave the said arefying or drying chambers with facility after having operated on the meat or other material to be dried or subjected to arefaction. 95 The spaces A B, between the outer longitudi-

nal walls and the perforated sheet-metal walls N, serve to facilitate the circulation of the heated air. The exterior cold air descends on the longer sides of the heating-chamber 5 through suitable gratings, g, is heated by coming in contact with the large heating-surface of the ribbed tubes or pipes a' a' b' b' c' c', and flows upward over the somewhat inclined ceiling of the heating-chamber to the inlet intermediate space, A. The inlet and outlet spaces A and B are, as stated, separated from the heating-chamber by perforated sheet-metal walls N. Bracket-like projecting sheets of metal or other suitable material, d d, Figs. 1 15 and 4, are arranged in the inlet-space in order to distribute the heated air equally in all the drying or arefying chambers M. The heated air enters from the inlet-space A through the perforated sheet-metal wall N into the drying or arefying chambers M, and passes 20 through the opposite perforated metallic wall, N, into the outlet-space B, and from thence to the flue or chimney. The temperature of the heated air should not be more than 60° 25 centigrade or 140° Fahrenheit, and is indicated by a suitable thermometer. The meat or other material to be dried or subjected to arefaction is first hacked or reduced, and is then spread in suitable thickness (generally 30 about five-eighths inch) on suitable wire sieves or perforated slides, P. (See Figs. 7 and 8.) These said wire sieves or slides P are moved slowly forward from one end of the apparatus to the other by means of suitable chains, R, 35 passing over chain-wheels S, secured to suitable shafts or axles, T, so that a continuous operation is attained. Projecting rows of knives V, placed at a suitable angle to each other, are attached to the roof of each drying or arefying 40 compartment, in order to communicate a slight movement to the meat or other material treated,

and in order to attain the correct drying or arefaction of the same and to prevent the material sticking to the wire of the sieves or shelves. The axles or shafts T to the chain-wheels S are connected to the driving-drum H by gearing W, and each of the said shafts may be provided with ordinary means whereby they may be coupled or uncoupled, as may be requisite. 45

The said axles or shafts for the chain-wheels can be driven by means of the bevel-wheels, as shown, or any other suitable device may be employed. 50

Having now described my said invention 55 and the manner of carrying the same into effect, I wish it to be understood that I do not confine myself to the special form of the parts or the special arrangement of the same, as these can be varied without departing from 60 the tenor of my said invention.

What I claim, and desire to secure by Letters Patent in a drying or arefying apparatus for meat and other materials, is—

1. The combination and arrangement, substantially as shown and described, of the sieves or shelves and means to move them, the heating-chamber in which they move provided with the foraminous walls N and outer close walls, K, and the stationary inclined or slanting knives V, as and for the purpose set forth. 65

2. The combination and arrangement of the drying or arefying chambers M and the spaces or passages A and B, for the introduction and escape of the heated air, with the canals provided with suitable gratings for the admission of cold air, and with the canals 1 2 3 4 of the heating apparatus, substantially as described. 70 75

DAVID GROVE.
